Specification for Design.

Patented Jan. 19, 1915.

Application filed July 25, 1914. Serial No. 853,175. Term of patent 14 years.

To all whom it may concern:

Be it known that I, HENRY B. NEWHALL, Jr., a citizen of the United States of America, and residing at Plainfield, in the county of Union and State of New Jersey, have invented a new, original, and ornamental Design for Paper-Cutters or Similar Articles, of which the following is a specification, reference being had to the accompanying drawing, in which—ter embodying my design. Fig. 2, is a side view of the same.

I claim—

The ornamental design for a paper cutter or similar article, substantially as shown or any colorable imitation thereof.
